UNITED STATES PATENT OFFICE.

NELSON WALDRON, OF NEW YORK, N. Y.

THEATER APPLIANCE.

SPECIFICATION forming part of Letters Patent No. 245,895, dated August 16, 1881.

Application filed June 22, 1880. (Model.)

To all whom it may concern:

Be it known that I, NELSON WALDRON, of the city of New York, in the county and State of New York, have invented certain new and 5 useful Improvements in Theater Appliances, of which the following is a specification.

My invention relates to appliances for theater-stages, in which there is combined with the stage proper two or more movable stages, one 10 above the other, which may be raised or lowered so as to bring either of them to the level of the stage proper. Such a construction has been adapted to facilitate the setting of the 15 scenery of different acts of a play or opera, as the scenery may be set on one of the movable stages while an act is being played upon the other, or one of the other movable stages, and it also effects an economy of space upon the stage of a theater.

20 Such a system of movable stages is necessarily of great weight; and the object of my invention is to so apply the mechanism for raising, lowering, and balancing the stages that they may be quickly raised and lowered by a small 25 amount of power.

The invention consists in the combination, with a stage proper, of two or more movable stages arranged one above the other, ropes connected to the corners or sides of said 30 movable stages, sheaves or pulleys over which said ropes pass, a saddle to which said ropes are connected, a rope connected to said saddle, and a drum over which the last said rope passes, and by the rotation of which the movable 35 stages are raised or lowered.

The invention also consists in the combination, with said stages, hoisting connections, saddle, hoisting-rope, and drum, of counter-weights, which are connected with said parts 40 in a novel manner.

The invention also consists in the combination, with the movable stages, of borders, border-lights, traps, and numerous other theater appliances, in a manner hereinafter fully described, and in various details of construction and combinations of parts pertaining to said hoisting mechanism.

In the accompanying drawings, Figure 1 represents a vertical section through a theater-stage and a side view of two movable stages

and hoisting mechanism for raising and lowering the same. Fig. 2 represents a plan thereof. Fig. 3 represents a side view of the hoisting mechanism, and Fig. 4 represents a plan thereof.

55

Similar letters of reference designate corresponding parts in all the figures.

A designates the stage proper. B and C designate, respectively, two movable stages, arranged one above the other, and constructed 60 with corner-posts B', connecting said stages. The openings in the floors through which the stages pass are preferably furnished with friction-rollers a, which properly guide the stages and diminish the friction caused by their movement. The movable stages B and C, being connected with suitable raising, lowering, and balancing mechanism, may be raised and lowered, and while an act is being played upon one 65 stage the scenery may be arranged upon the other. Although but two movable stages are here shown, three, or indeed more, might be employed.

To each of the four corners or sides of the 70 movable stages is attached a hoisting-connection. The ropes b in the present example of my invention form these hoisting-connections, and pass upward over sheaves or pulleys E, set at different angles, as clearly shown in Fig. 2, and thence downward to a saddle, F, to which 75 all of said ropes are connected by means of rods or by ropes c. (Shown in Fig. 3.) In lieu of this arrangement, however, rods or ropes forming hoisting-connections might be attached to opposite corner-posts upon each side 80 of the stages, and connected to each other by a bridle, to the middle of which a rope might be attached, whereby two ropes would extend to the saddle instead of four, as now shown. Connected to this saddle is a hoisting-rope, d, which 85 is attached to a hoisting-drum, G, by the rotation of which the stages are raised and lowered.

It is obvious that as the four corners of the 90 stages are connected to the saddle and a single hoisting-rope employed, the corners of the stages are raised simultaneously, and all binding or canting is obviated.

The weights for balancing the movable 95 stages might be connected to each of the four 100

corners of the movable stages by independent ropes passing over independent sheaves or pulleys; or they may be connected to the saddle F; or, if desirable, and as here represented, 5 a portion of the weight may be balanced by the corner weights and the remainder by a weight attached to the saddle.

To the corners of the stages are connected ropes l, which pass upward over sheaves K, 10 and thence downward to counter-weights L, each composed of a number of separate sections, so that the weights may be readily increased or diminished.

From the ends of the saddle F are suspended 15 rods or ropes e, to the lower ends of which the balancing-weight H, also composed of separate sections, is attached, and when this construction is employed the hoisting-rope d may be passed several times around the hoisting- 20 drum G, and thence downward, and connected to the balance-weight H. When so constructed the hoisting is effected by the friction of the hoisting-rope upon the drum G; but the hoisting-rope might be secured in the periphery of 25 the drum.

The mechanism for imparting motion to the drum G consists, in the present instance, of a gear-wheel, I, arranged upon the shaft of the drum G, and receiving motion from pinions f 30 upon shafts g, which, in turn, receive their motion through gear-wheels h from shafts i, which carry cranks j and fly-wheels k for operating the hoisting mechanism. These parts are supported in suitable bearings in a frame or housing, J, which is to be connected to the wall of 35 the building or other suitable support.

When movable stages are employed the traps, borders, border-lights, and other stage appliances should be arranged upon or attached to 40 the stages.

In this example of my invention the lower of the two stages B is furnished with a trap-floor, M, at a little distance below it, and the other stage might also be constructed with 45 such a trap-floor. I have represented a large trap, N, and two quarter-traps, O, as arranged upon this floor and adapted to be raised and lowered in guides n by means of ropes o, passing over windlasses p, or otherwise suitably 50 arranged. These traps may be furnished with counter-weights, so as to balance their weight.

P designates borders attached to both stages, and P' designates border-lights arranged in proper relation thereto. The borders are suspended, in the usual manner, by ropes or lines r, attached to the upper edges thereof, and passing over pulleys s to the side of the stages, where they can be readily reached from the fly-floors Q for the purpose of adjusting the 55 borders. The pipes P', which form the border-lights, are all connected to an upright pipe, R, which is connected at its lower end to the main gas-pipe by a flexible tube, u, so as to permit of the rising and falling of the stages. 60

The movable stages are also constructed 65 with the ordinary slots, sinks, and other appurtenances for setting and arranging scenery, the same as a fixed stage.

The movable stages thus constructed may be so nearly balanced by counter-weights that 70 they can be readily raised and lowered and enable the acts of a play or opera to follow one another without intermission, and the construction and arrangement of the raising, lowering, and balancing devices is such that it 75 enables a system of heavy stages, weighing from twenty-five to forty tons and upward, to be raised and lowered by one or two men.

I am aware that it is not new to employ in connection with the stage proper of a theater 80 two movable stages which may be raised or lowered to bring either of them into coincidence with the stage proper, and hence I do not claim this, broadly, as my invention.

What I claim as my invention, and desire 85 to secure by Letters Patent, is—

1. The combination, with a stage proper, of two or more movable stages, arranged one above the other, a series of ropes connected with the corners of said movable stages, 90 sheaves or pulleys over which said ropes pass, a saddle to which the other ends of said ropes are connected, a hoisting-rope connected to said saddle, and a drum upon which the last said rope is wound, and by the rotation of 95 which the movable stages are raised and lowered, substantially as specified.

2. The combination, with the stage proper, the movable stages, the ropes connected to the movable stages at the corners, and the saddle 100 to which said ropes are severally connected, of the counter-weight suspended from said saddle, and the drum and rope by which the raising and lowering of the movable stages is effected, substantially as specified. 105

3. The combination of the saddle F, the counter-weight H, suspended therefrom, the drum G, and the hoisting-rope d, attached to said saddle, passing around the drum and thence downwardly, and connected to the counter-weight, the whole arranged substantially as specified. 110

4. The combination of the movable stages B C, the ropes b, connected to the corners thereof, the sheaves E, over which said ropes 115 pass, the saddle F, the hoisting-drum G, the hoisting-rope d, attached to said saddle and wound around or secured to the drum, the counter-weight H, and the independent counter-weights L, attached by independent ropes l 120 to the corners of said stages, all substantially as specified.

5. The combination, with the stage proper and a movable stage, of a trap-floor attached to and arranged below the movable stage, one 125 or more traps arranged upon said floor, guides for said traps, and windlasses for raising the traps mounted upon said floor, all constructed
